UNITED STATES PATENT OFFICE.

FRANK GEORGE RYTHER, OF COPENHAGEN, NEW YORK.

MAIL BOX.

Application filed October 4, 1923. Serial No. 666,486.

To all whom it may concern:

Be it known that I, FRANK GEORGE RYTHER, a citizen of the United States, residing at Copenhagen, in the county of Lewis and State of New York, have invented a new and useful Improvement in Mail Boxes, of which the following is a specification.

This invention relates to mail boxes of the kind commonly used on rural delivery routes.

Mail boxes of this kind are generally placed in positions where they are exposed to the weather and it is consequently desirable to provide a box which is so constructed as to protect the contents of the box from the weather and to enable the box to be readily opened and closed, even when coated with ice or sleet.

The objects of this invention are to provide a box of this kind of improved construction which is so made as to protect various parts of the box as well as the contents of the box from the action of the weather by providing a cover portion which is adapted to enclose the body portion of the box and the operating mechanism; also to provide mechanism of improved construction for raising and lowering the cover portion and for holding the same in open position to expose the body portion of the box; also to provide means for guiding the cover portion in its movement into and out of its closed position; also to improve the construction of mail boxes of this kind in the other respects hereinafter specified.

In the accompanying drawings:

Fig. 1 is a front elevation of a mail box embodying my invention.

Fig. 2 is a side elevation thereof.

Fig. 3 is a sectional elevation thereof on line 3—3, Fig. 5, on an enlarged scale.

Fig. 4 is a similar sectional elevation thereof showing the parts of the box in different positions.

Fig. 5 is a central sectional elevation thereof on line 5—5, Fig. 3.

Briefly stated, the mail box embodying the invention which is shown in the accompanying drawings includes a body or receptacle portion which is open at its upper end and which is adapted to contain the mail matter, a cover portion which telescopes or fits loosely over the body portion and covers either all or the greater part of the body portion, and actuating mecha-

nism for lifting the cover portion so as to move the same upwardly clear of the body portion and then swing the cover portion backwardly to expose the upper open end 60 of the body portion, the lifting mechanism being arranged under the cover portion in such a manner as to protect the mechanism against the weather.

A represents the body portion of the box 65 which, in the construction shown, has its upper end open to receive the mail matter. This body portion may be of any desired shape and the bottom thereof is rigidly secured to any suitable support, for example, 70 in the construction illustrated, a pair of feet or legs *a* of any suitable form are secured to the bottom of the box and are mounted upon a base or platform *a'* mounted on a post *a''*. Other means for mounting 75 the body portion of the box on a support may be employed if desired.

B represents the cover portion of the mail box, the lower part or skirt portion *b* of which corresponds substantially in shape 80 with the outer walls of the body portion A and is adapted to surround the side walls of the body portion. The upper part of the cover portion of the box includes a roof *b'* secured to the sides of the cover 85 portion of the box. Preferably the sides *b* of the cover portion are provided with an inwardly extending flange *b''* which is adapted to rest on the upper edges of the body portion of the box when the cover portion 90 is in its closed or operative position on the body portion. The front and rear walls of the lower or skirt part of the cover fit closely to the corresponding walls of the box body portion A and the opposite side 95 walls of the cover portion are preferably spaced a little farther from the end walls of the body portion so as to provide room for the raising and lowering mechanism 100 of the mail box. The lower part or skirt of the cover portion of the box preferably extends, as in the construction shown, to the lower edges of the box body portion so as to entirely cover the body portion. Consequently, when the box is subjected to 105 sleet or other weather conditions which would form a coating of ice on the box, this coating of ice or sleet will be formed entirely on the cover portion of the box and will not touch the body portion, thus 110 leaving the cover portion at all times free to move upwardly into its open position.

In uncovering the body portion of the box, it is desirable to first raise the cover portion in a vertical direction and then tilt the same rearwardly. The mechanism for accomplishing this movement is preferably constructed as follows: C represents a hand lever which is arranged at one side of the mail box and by means of which the cover portion may be raised and lowered. The lower end of this lever is rigidly connected to one end of a shaft or rod c which is suitably journalled on a fixed part of the box. In the construction shown, a pair of straps c' is suitably secured to the bottom of the body portion of the box and are bent to form bearings for the rod c. The rod or shaft c extends slightly beyond the opposite ends of the body portion of the box, and a pair of arms D is rigidly secured to the shaft adjacent to the opposite ends thereof. These arms extend into the space between the ends of the body portion of the box and the end walls of the cover portion, and when the cover portion of the box is in its closed position the arms D are arranged adjacent to the lower portion of the box as shown in Fig. 3. The outer ends of these arms are pivotally connected to links E and the other ends of the links E are pivotally connected to the end walls of the cover portion of the box at a point in advance or in front of the longitudinal center of the cover portion.

Means are preferably provided for swinging the cover portion of the box rearwardly into the inclined or tilted position shown in Fig. 4, and for holding the cover portion in this position so that the cover will be in readiness to be moved back into its closed position. In the construction shown for this purpose, a pair of rigid arms F is provided which extend upwardly along the rear wall of the cover portion and which are spaced at a distance therefrom and which have their upper ends f extending inwardly toward the box to form stops with which corresponding stop projections g on the cover portion of the box are adapted to engage when the cover portion of the box has reached the upper limit of its upright movement. When the stops g engage the stops f, further upward movement of the links E will cause the cover portion to swing or tilt rearwardly, and this rearward tilting of the cover portion is also assisted by the arrangement of the pivotal connection of the link E and the cover portion in advance of the central transverse plane thereof. When the cover has been swung to the limit of its opening movement, the upper faces of the stop projections f will support the cover portion in a position from which it can be readily swung into its closed position. The rigid arms F, in the construction shown, are provided with lower portions f' secured to the body portion of the box. The pro-

jections g of the cover portion of the box may be of any suitable construction, those shown including straps G secured to the rear wall of the cover portion of the box and having their lower ends bent outwardly to form the stop projections g. The straps G also serve the purpose of cooperating with the ends of the stops f to guide the cover portion during its vertical movement, to prevent wear on the cover portions of the box.

The operation of the box opening and closing mechanism is as follows: When the lever C is swung backwardly through about a quarter turn from the position shown in Fig. 2, the shaft c will be rotated through a corresponding angle, causing the arms D to be raised and to exert upward pressure on the links E which consequently slide the cover portion of the box upwardly in a substantially vertical direction, the movement of the cover portion of the box being guided by the front and rear sides of the body portion thereof and by the engagement of the stops f with the straps G. When the cover portion of the box has been raised so as to almost clear the body portion, or in other words to a point at which the side walls of the body portion of the box no longer acts as guides for the cover portion, the cover portion is held against swinging beyond the position shown in Fig. 4 by engagement of the arms D with the lower rear edge of the cover portion of the box.

The front wall of the cover portion of the box may be provided with an indicating device or signal which may be exposed when the box contains mail matter. In the construction shown for this purpose, a visible signal or panel H is provided which may be of any suitable design and which may be concealed by means of a door hinged to the front wall of the cover portion and having a catch h' cooperating with a fixed catch h² on the cover portion of the box for holding the door in its closed position. When this door is open it indicates that the box contains mail matter which should be removed, and when the door is closed, it indicates that the box is empty.

I claim as my invention:

1. In a box, the combination of a box body portion, a cover portion therefor having a depending skirt surrounding said box body portion, mechanism for moving said cover portion upwardly in a substantially vertical direction, and means engaging said cover portion after a predetermined upward movement thereof to convert the upward movement imparted thereto by said mechanism into a tilting movement.

2. A mail box including a box body portion, a cover portion adapted to be moved downwardly to enclose the greater part of said body portion, mechanism for raising

- said cover portion, said mechanism being arranged in the space between said body portion and said cover portion and being protected from the weather by said cover portion, and a handle connected with said mechanism for actuating the same, said handle being arranged outside of said cover portion and movable relatively thereto.
5. In a mail box the combination of a box body portion, a cover portion therefor having a depending skirt surrounding said box body portion, mechanism for moving said cover portion in a substantially vertical direction, and a stop for engaging said cover portion for tilting the same after a limited movement in a vertical direction.
6. In a mail box the combination of a box body portion, a cover portion therefor having a depending skirt surrounding said box body portion, mechanism for moving said cover portion in a substantially vertical direction, a stop member on said cover portion, and a fixed stop member with which said first-mentioned stop member is adapted to engage after a limited vertical movement of said cover portion, to cause said cover portion to be tilted.
7. In a mail box, the combination of a box body portion, a cover portion having a depending skirt which is adapted to surround said body portion, a rod journalled to said body portion, arms connected to said rod and extending into the spaces between the skirt of said cover portion and said box body portion and pivotally connected with said cover portion for raising and lowering the same, and means for turning said rod to effect the raising and lowering of said cover portion.
8. In a mail box, the combination of a box body portion, a cover portion having a depending skirt which is adapted to surround said body portion, a rod journalled on said body portion, arms extending outwardly therefrom and pivotally connected with said cover portion, and cooperating stops which limit the upward movement of the rear end of said cover portion and cause said cover portion to tilt after a predetermined vertical movement thereof, said arms engaging with said rear end of said cover portion to limit the swinging movement of said arms for limiting the opening movement of said cover portion.
9. In a mail box, the combination of a box body portion, a cover portion having side walls surrounding the side walls of said box body portion, a rod journalled on said body portion, arms extending outwardly therefrom and pivotally connected with said cover portion, and a depending skirt surrounding said body portion when said cover is in its closed position, mechanism for moving said cover portion upwardly to clear said box body portion, said mechanism being covered by said cover portion when in its closed position, and a stop for tilting said cover portion after a limited upward movement thereof.
10. In a mail box, the combination of a box body portion, a cover portion having a depending skirt surrounding said body portion when said cover is in its closed position, mechanism for moving said cover portion upwardly to clear said box body portion, said mechanism being covered by said cover portion when in its closed position, and a stop for tilting said cover portion after a limited upward movement thereof.

FRANK GEORGE RYTHER.
